UNITED STATES PATENT OFFICE

99,252

DESIGN FOR A HANDLE ADAPTED FOR A DRAWER OR SIMILAR ARTICLE

John Tjaarda, Birmingham, Mich., assignor to Briggs Manufacturing Company, Detroit, Mich., a corporation of Michigan

Application August 7, 1935, Serial No. 57,996

Term of patent 14 years

To all whom it may concern:

Be it known that I, John Tjaarda, a subject of the Netherlands, residing at Birmingham, county of Oakland, State of Michigan, have invented a new, original, and ornamental Design for a Handle Adapted for a Drawer or Similar Article, of which the following is a specification, reference being had therein to the accompanying drawing, forming a part thereof, in which

Fig. 1 is a top plan view showing my new handle design.

Fig. 2 is a side elevation thereof; and
Fig. 3 is a vertical section taken substantially along the line 3—3 of Fig. 2.

I claim:

The ornamental design for a handle adapted for a drawer or similar article, substantially as shown.

JOHN TJAARDA.
